United States Patent Office.

LYMAN B. PRINDLE, OF LITCHFIELD, CONNECTICUT.

Letters Patent No. 73,833, dated January 28, 1868.

IMPROVEMENT IN LIFTING-JACK.

The Schedule referred to in these Letters Patent and making part of the same.

TO ALL WHOM IT MAY CONCERN:

Be it known that I, LYMAN B. PRINDLE, of the town and county of Litchfield, in the State of Connecticut, have invented certain new and useful Improvements in Lifting-Jacks for wagons, and for other purposes; and the following is a full, clear, and exact description of the same, reference being had to the accompanying drawings, making a part of this specification, in which—

Figure 1 represents a side view of the jack, with the lifting-lever shown in different positions in red and blue lines.

Figure 2 are front and perspective views of the extension-pawl, as in fig. 1.

The object of my invention is simplicity and cheapness, and it consists in an extension-pawl, in combination with a ratchet-lever and single-mortised standard, having a series of notches, in which the fulcrum of the lever may be placed, according to the height of the article to be lifted.

To enable others to make and use my improved wagon or lifting-jack, I will describe it more in detail, referring to the drawings, and to the letters marked thereon.

I make the standard A of a single piece of hard wood, having a series of notches, *a a a*, and a long mortise in the upper end, through which the lever B passes; the lever B having a fulcrum-pin, *b*, to be placed in any of the notches *a a a*, when it will be in the most suitable position to lift the thing to be raised, the lever B being provided with a ratchet, *c c*, on its top edge, for the extension-pawl C to work in as the outer end of the lever B is depressed. The extension-pawl C may be made with a stem, D, which is pivoted to the upper end of the mortise in the standard A, the pawl C made to slide on it, having a slit, *e e*, through which a thumbscrew, *d*, passes to hold it to the stem D in any place it may be desirable to have it, to hold the weight on the end E of the lever B, so that, if the lever-fulcrum is in the lower notches, the pawl must be elongated to correspond with the position of the lever, and also shortened up as the fulcrum of the lever is raised in the notches *a a a*.

Thus it will readily be seen that a universal lifting or wagon-jack can be made in a very simple and cheap manner, and is always in readiness for use, and can instantly be changed to take hold of the object at any height within the range or scope of the notches *a a a* and the opening through the standard A, and the lifting-lever B be kept in the proper position for the best action on the weight.

Having thus fully described my invention, what I claim as new, and desire to secure by Letters Patent, is—

The extension-pawl C D, as constructed, in combination with the ratchet or notched lever B, and the single-mortised and notched standard A, whereby the fulcrum of the lever may be placed in any position for the height of the article to be raised, as herein set forth.
